UNITED STATES PATENT OFFICE.

GEORGE W. HOYLE, OF SANTA ROSA, CALIFORNIA.

INVALID'S AND CRIPPLE'S BED APPLIANCE.

Application filed March 25, 1924. Serial No. 701,707.

To all whom it may concern:

Be it known that I, GEORGE W. HOYLE, a citizen of the United States, residing at Santa Rosa, county of Sonoma, State of California, have invented certain new and useful Improvements in Invalids' and Crip-
ples' Bed Appliances; and I do declare the following to be a full, clear, and exact description of the same, reference being had
10 to the accompanying drawings, and to the characters of reference marked thereon, which form a part of this application.

This invention relates to improvements in devices for the purpose of aiding in the handling of bed-ridden people, my principal object being to provide an appliance for the purpose adapted to be removably located adjacent the bed in which the patient is lying, and provided with various independently or simultaneously operated devices for supporting and raising the entire body of the patient as a whole, or for supporting one or more limbs in a fixed position while enabling the other portions of the body to be raised.

The necessity for raising a patient off the bed at various times is well known to anyone who has had sick room experience, and such persons are also aware of the hard and difficult work it very often is to raise the sick or helpless, as many as three persons being frequently necessary to satisfactorily perform the operation in the old way. Besides this, the practical impossibility of the raising movements of the attendants being timed so as to be in unison, very often causes great pain and discomfort to the patient.

With my improved appliance, a patient no matter if paralyzed, excessively weak from sickness or perhaps entirely well except for a broken limb, may be easily and quickly raised any necessary distance, and with but very little effort on the part of a single attendant being necessary.

45 The appliance is provided with different and independent forms of body supporting elements adjustable to suit different conditions, which elements may or may not be raised together, depending on whether or not this is desirable.

50 The appliance being absolutely independent of the bed, the latter may be withdrawn, and another and different form of bed, or a wheeled chair, may be placed under the appliance and into which the patient in the latter may then be lowered.

A further object of the invention is to produce a simple and inexpensive device and yet one which will be exceedingly effective for the purpose for which it is designed.

60

These objects I accomplish by means of such structure and relative arrangement of parts as will fully appear by a perusal of the following specification and claims.

65

In the drawings similar characters of reference indicate corresponding parts in the several views:

70

Figure 1 is a perspective view of the complete appliance as fitted up for ordinary invalid cases.

Fig. 2 is a fragmentary view of the appliance at the rear end thereof, showing a leg sling arranged in a nonraisable position.

75

Fig. 3 is a similar view, showing the leg sling as arranged to be raised or lowered.

Fig. 4 is a fragmentary longitudinal section of a hook-supporting arm, showing a hook therein.

Fig. 5 is a perspective view of the hook detached.

80

Fig. 6 is a fragmentary view of a hammock and its connecting means.

85

Referring now more particularly to the characters of reference on the drawings, A designates two end-frames, each consisting of a pair of standards 1 converging upwardly and rigidly connected together at their upper ends by means of a plate 2 and at their lower ends by a horizontal bar 3. At an intermediate point, each pair of standards 1 is connected by a cross-bar 4. At the head-end of the appliance, a central standard 5 connects two cross-bars 3 and 4, while at the foot-end of the appliance these two cross-bars are connected by a pair of standards 6. The two bottom braces 3 are connected by a longitudinal bar 7, but this bar is made readily removable in order that the bed may be readily wheeled into position between the standards without lifting it from the floor.

90

The plates or brackets 2 are rigidly connected by a top-bar 8 which is desirably made of a series of short tubes connected together by couplings 9 nonturnably mounted thereon, each of which is provided with a pair of oppositely-extending nipples 10 internally threaded for the reception of the threaded end of removable tubular bars 11, a number of these bars 11 being provided and all being interchangeable, to the end that the bars may be attached to the top-rod at vari-

95

105

110

- ous points in the length thereof. Each of the supporting-bars 11 is desirably made hollow and provided with a slot 12 along its under side to enable a pendent hook 13 to be adjustably supported on the bar. The shank of the hook extends through the slot and the upper end of the shank is provided with a head 14 rounded on its under side to fit the interior of the tube, each head being provided with an upstanding sharpened tooth 15 adapted to bite into the top side of the tube when a weight is hung on the hook 13, to thus automatically anchor the hook on its adjusted position.
- 15 Journaled in the brackets 2, parallel to and immediately below the top-rod 8, is a shaft 16 provided at various points in its length with oppositely-extending pairs of pins 17 and having attached at one end a sprocket-wheel 18. A sprocket-chain 19 connects this wheel 18 to another sprocket-wheel 20 journaled on the adjacent cross-brace 4 and is adapted to be rotated by means of a crank-handle 21.
- 25 To hold the handle from turning when desired, the adjacent members 4 and 5 are horizontally orificed as at 22, to removably receive a pin 23 then projecting into the path of movement of the handle.
- 30 Hung on certain longitudinally spaced ones of the pins 17 is a pair of ropes or cables 24, whose lower ends are looped as at 25 to slip over the respective ends of a pair of side bars 26 adapted to be removably passed through hemps 27 formed lengthwise at the edges of a sheet 28 of canvas or the like and forming a hammock. To hold the loops 25 from possibly sliding off the bars 26, the latter have collars 29 on their ends, 40 and to prevent the loops from sliding along the bars, I apply to each cable and the adjacent bar end a double hook member 30, the bars being hollow and open-ended. Spreader or spacer bars 31 are adapted to be removably attached to the ends of the bars 26 and to extend transversely therebetween, the length of the spacers being sufficiently less than the width of the canvas, so that when the spacers are applied, the canvas will 45 have a considerable sag, as shown in Fig. 1. The purpose of this arrangement will be seen hereinafter.
- 50 The hammock 28 is located under the head end of a bed in connection with which the appliance is to be used. It should be of sufficient length to extend from above the head of a patient down to the hips, and its width should be at least equal to that of the bed, for the reason hereinafter seen.
- 55 To support the legs of the patient, different forms of slings or hammocks, usable in conjunction with the main hammock 28, may be employed, depending on different conditions to be met.
- 60 Three different types and arrangement of

such additional hammocks or slings are shown in Figs. 1, 2 and 3.

The lower-end form of hammock 32 shown in Fig. 1 is practically identical in construction, shape and manner of supporting the same as the main hammock 28, though possibly somewhat shorter and narrower if desired. The cables 33 which support this lower hammock are looped over certain of the pins 17 so that a space of a foot more or less is had between the two hammocks. In the lower hammock, the spreader bars may or may not be used, this depending on the circumstances of the case. This hammock arrangement is usable when the patient is sick but is not afflicted with a broken lower limb.

In the latter case, a leg sling 34 as shown in Figs. 2 and 3 may be employed to support the broken or fractured member. If both legs are broken, two independent slings are of course used, though I have only deemed it necessary to show one of the same.

There are several ways in which this sling may be supported, two of which are shown in said figures.

If it is desired to support the leg in a fixed horizontal position at all times, irrespective of the raising of the remainder of the body, the cables 35 of the sling may be connected directly to the hooks 13 carried by the arms 11, which would be positioned in those ones of the nipples 10 which are properly located, as shown in Fig. 2.

Since the hooks are adjustable in the slotted arms, the spacing of the sling from the center of the bed, or its angular positioning relative to the longitudinal plane thereof, may be altered at will.

If the leg is in such a condition that it may be raised and lowered with the rest of the body, a number of sheaves 36 (See Fig. 3) is supported by the hooks 13 of suitably located arms 11, these hooks being disposed adjacent opposite ends of the arm-slots.

Individual cables 37, looped at one end over adjacent pins 17 pass around the sheaves and are suitably connected at their lower ends to the sling 34.

To enable a fractured limb to be maintained in a stretched condition, as is desirable, I provide each standard 6 with a vertical and longitudinally disposed slot 39, and with a plurality of vertically spaced bolt holes 40 crossing the slot.

Mounted in the slot is a sheave 41, held in a vertically adjustable position by means of an axial pin 42 removably passed through any of the holes 40. The positions of the sheave may thus be adjusted to any height within the range of the slot.

A cord or cable 43 is run over the pulley and carries at its lower end a suitable weight 44 while its opposite end is attached to a

leg-cast 45 or the like as indicated in Fig. 2. If a person has a broken arm, an arm sling may depend from a bar 11 located near the head of the bed, and entirely independent of the hammock 28.

In operation, with the type shown in Fig. 1, the canvases 28 and 33 are normally outstretched on the bed with suitable bed coverings, such as a sheet etc. over the same, and on which the patient lies, these canvases being so placed before the patient first occupies the bed.

At such times, the side bars 26 are removed from the canvases and kept under the bed or in any other suitable location, and the various ropes are hung up out of the way on the frame of the appliance.

When it is desired to raise the patient, the side edges of the canvases are uncovered so as to enable the bars 26 to be slipped into place in the hems 27, and the ropes 24 and 33 are connected to the proper ends of the bars as hereinbefore described.

The handle 21 is then turned to the right so as to cause the ropes to be wound about the shaft sufficiently to raise and draw together the sides of the canvases to a point above the body of the patient without actually raising him. Rotation of the shaft is then halted while the spacers 31 are placed in position, preventing further converging movement of the sides of the canvases and converting them into hammocks of definitely maintained sizes, in which the patient may lie without discomfort and without the danger of a further lifting of the canvases tending to wrap about and squeeze him. Further rotation of the shaft will then cause the hammocks, with the patient lying therein, to be raised easily and quickly to any desired distance, and with the aid of but a single attendant, since one person can if necessary connect 'up the canvases to their ropes, place the spacer bars, and turn the raising-control handle.

The bed may then be pulled out and aired or remade before lowering the patient back into the bed.

Duplicate sets of the canvases should be kept, so that when necessary a fresh set, and clean coverings, may be laid out on the bed while the patient is supported by another set. Then when the patient is again lowered into bed, the original set may easily be drawn out from under the patient.

If a type of sick bed is used whose head portion slopes upwardly, the hammock may be made to assume the desired angle by slipping the ropes lengthwise over the pins, so that the head end will be raised and the other end lowered.

If the appliance is only used by a single individual, it may be permanently stationed over the bed, since it does not interfere in

any way with the ministrations of a nurse or doctor.

If the device is used in a hospital, it may be easily shifted from one bed to another as the occasion demands, since its use in connection with any one patient at a time is but temporary.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A bed appliance including a vertical and rigid frame, adapted to straddle a bed lengthwise thereof, a plurality of body supporting elements arranged between the end members of the frame, means supporting one of said elements in a manner to enable the same to be raised and lowered at will, and means supporting the other element from the frame in a manner to enable the transverse position of the same relative to the other element to be altered at will while enabling both elements to be raised and lowered in common.

2. A bed appliance including a vertical and rigid frame, adapted to straddle a bed lengthwise thereof, a horizontal shaft journaled in the frame and extending lengthwise of the bed, a plurality of radial and longitudinally spaced pins on the shaft, a hammock, and cables attached to the hammock and adapted to be detachably connected to any of the pins in a manner to cause the cables to be raised and lowered upon the turning of the shaft.

3. A bed appliance embodying a frame adapted to straddle a bed lengthwise thereof, a shaft journaled in the upper end of the frame and provided with projecting pins, a hammock, and a pair of cables connected to the four corners of the hammock and adapted to be slidingly looped over the pins.

4. A bed appliance comprising a frame adapted to be adjusted astride a bed lengthwise thereof, a longitudinal bar in the top of the frame provided with a plurality of sockets at spaced intervals, and a plurality of supporting-bars each of which is adapted to be engaged with any one of said sockets, each of these supporting bars being provided with means for supporting a sling.

5. A bed appliance comprising a frame adapted to be adjusted astride a bed lengthwise thereof, a longitudinal bar in the top

of the frame provided with a plurality of sockets at spaced intervals, and a plurality of supporting-bars each of which is adapted to be engaged with any one of said sockets, 5 each of these supporting-bars being provided with a pulley support, each of said pulley supports being longitudinally adjustable along the bars.

6. A bed appliance comprising a frame 10 adapted to be adjusted astride a bed lengthwise thereof, a longitudinal bar in the top of the frame provided with a plurality of sockets at spaced intervals, and a plurality of supporting-bars each of which is adapted 15 to be engaged with any one of said sockets, each of these supporting bars being provided with a pulley support, each of said pulley supports being longitudinally adjusted along the bar, the adjustment means consisting of 20 a slot on the under-side of the bar and the

pulley support consisting of a pendent hook having a headed shank working in said slot, said head being provided with an upstanding tooth adapted to bite into the upper side of the tube when the hook is pulled downwardly. 25

7. A bed appliance embodying a frame adapted to straddle a bed lengthwise thereof, the frame at the foot-end thereof being provided with a pair of standards each 30 carrying a vertically-adjustable pulley adapted to carry the rope of a leg-sling, means for independently adjusting the pulleys consisting of a longitudinal slot formed in each standard and a plurality of holes extending transversely through the standard, and a removable bolt or pin adapted to serve as a journal for the pulley. 35

In testimony whereof I affix my signature.

GEORGE W. HOYLE.
